UNITED STATES PATENT OFFICE

2,654,203

BONDED DOFFER FOR MECHANICAL
COTTON PICKERSHoward F. Parkerton, South Gate, Calif., assignor
to International Harvester Company, a corpora-
tion of New Jersey

Application February 17, 1951, Serial No. 211,471

5 Claims. (Cl. 56—41)

1

This invention has to do with doffers for removing cotton from the picker spindles of cotton picking machines and more particularly concerns improvements in the means and method for securing spindle-engaging doffer pads onto a carrier therefor constituting elements of the doffer assembly.

A doffer assembly of the general character as that embodying the present invention, together with environment for such assembly, is disclosed in U. S. Patent 2,247,682. The doffer assembly shown in said patent comprises a metal disk having an annulus of rubber-like material secured to a face thereof by clamping elements. The rubber annulus includes a plurality of lug-like doffing pads projecting therefrom axially of the disk and spaced apart circumferentially thereof. These doffing pads are also of rubber and formed integrally with the rubber annulus, the lugs being pliable and resilient to facilitate their wiping engagement with the picker machine spindles to strip the cotton therefrom without injuring such spindles. To assure firm mounting of the rubber annulus upon the metal disk, such disk has been provided with projections respectively registering with the back sides of the doffing pads and projecting into nesting relation with cavities therein. Because of these metal projections into the pads they form limits beyond which the tips of the lugs cannot be worn away by abrasion during operation of the cotton picking machine, since it is essential that only the rubber-like material engage the spindles. An important object of this invention is the provision of a novel means and method for securing the doffer pads to the disk without the use of metal or hard material projections extending thereinto, whereby the pads can be worn away by the spindles to a greater extent and correspondingly decrease the frequency of doffer assembly servicing.

A further object of this invention is the provision of an attaching means whereby the doffing pads or a web with which they are integrally formed are attached directly to the carrier therefor by adhesion. This method of fabricating the doffer assembly diminishes weight in so far as clamping devices for securing the lugs to the plates are eliminated. Elimination of the clamping devices is also a factor contributing to diminution in production cost of these improved doffer assemblies.

These and other desirable objects inherent in and encompassed by the invention will be more clearly understood from the ensuing description, the appended claims and the annexed drawings, wherein:

Fig. 1 is an end view of a doffer assembly constructed in accordance with this invention.

Fig. 2 is an enlarged fragmentary sectional view taken on the line 2—2 of Fig. 1, illustrating the

2

means by which a rubber-like or elastomer unit embodying doffing pads is fabricated to a rigid disk unit of the assembly.

Fig. 3 is a view taken similarly to Fig. 1, illustrating a modified form of the invention which eliminates anchoring studs on the reverse face of the elastomer unit.

Fig. 4 is an enlarged fragmentary sectional view taken on the line 4—4 of Fig. 3.

Fig. 5 is a view taken similarly to Figs. 1 and 3, showing a third form of the invention wherein the elastomer doffing pads are discrete elements individually adhesively secured to the rigid plate carrier therefor.

Fig. 6 is an enlarged fragmentary sectional view taken on line 6—6 of Fig. 5.

With continued reference to the drawings and particularly to Figs. 1 and 2, there can be seen a disk-like carrier unit 11 having a hub 12 and formed symmetrically about a principal axis *a* seen as a point in Fig. 1. During operation of the entire doffer assembly 13 it is caused to rotate about the axis *a*.

The disk-like unit 11 has an annular face 14 disposed substantially within a plane at right angles to the axis *a* and arranged coaxially therewith. This annular face 14 constitutes one side of a flat annular rim portion 15 containing a plurality of holes 16 communicating through the face 14 and spaced apart circumferentially of the unit 11 as shown in Fig. 1. An annular shoulder 17 which borders the inner perimeter of the annular face 14 projects axially of the disk-like unit from such face.

An integral unit 18 of elastomer material comprises an annular wafer-like web 19 having an obverse face 21 and a reverse face 22 conforming to the annular face 14 of the disk-like unit 11. Anchoring studs 23 project from the reverse face 22 respectively into the plate holes 16. The inner perimetric edge 24 of the web 19 rests against the shoulder 17 whereas a circular flange 25 of the web 19 extends along the outer perimetric edge thereof and projects axially of the plate 11 from the reverse face of such web in contiguity with the outer perimetric edge 26 of the plate. A plurality of doffing lugs or pads 27 project axially from the obverse face 21 of the elastomer unit 18.

The elastomer unit 18 may be formed of natural rubber, synthetic rubber-like material, or a blend of these two materials. The material from which the unit 18 is made preferably possesses the characteristic of soft vulcanized rubber having a resistance to displacement and elasticity proximating that of tread projections on conventional automobile tires. This material is vulcanizable and is attached to the face 14, the shoulder 17, the perimeter 26 and the circular edges about the openings 16 by being pressed thereagainst while in an unvulcanized condition pursuant to being

molded to form the web 19, studs 23 and the pads 27. While the plastic unvulcanized material is held in this molded formation, heat is applied thereto for producing the vulcanized condition attendant to which an adhesive bond is effected with the surfaces 14, 17, 26 and the rims of the openings 16.

The shoulder 17 provides a definite molding edge for the inner periphery of the elastomer web 19 to expedite the forming of the inner periphery of the web neatly and accurately. Furthermore, the shoulder 17 provides a guard for the inner edge of the web thereby preventing entry of any foreign object between the web and disk surface 14, and avoiding commencement of separation and peeling at this section. The elastomer flange 25 circumscribing the outer periphery of the disk provides a resilient guard and trim for the outer rim of the assembly 13, and because of being adhesively attached to the periphery 26 resists separation of the outer peripheral portion of the elastomer web from the disk face 14. Anchoring studs 23 are capable of absorbing shearing force against the edges of the openings 16 and thereby supplement the adhesive connection between the web and the face 14 in resisting sliding of the web upon said face.

In the form of the invention illustrated in Figs. 3 and 4, parts corresponding to those in the Figs. 1 and 2 embodiment are designated by the same respective reference characters plus the suffix "a". In this form of the invention there are no holes in the annular rim portion 15a of the plate-like unit 11a and consistent with this arrangement there are no studs on the reverse face of the elastomer web 19a. Prior to molding and pressing the elastomer unit 18a onto the plate-like carrier unit, the shoulder 17a, the annular face 14a and the outer periphery 26a are covered with a thin film 31 of vulcanizable rubber cement. Rubber cements of suitable character are commercially produced at many sources, a typical cement being sold under the trade-name "Plastilock" by The B. F. Goodrich Company of Akron, Ohio. This film 31 is vulcanized pursuant to vulcanization of the vulcanizable unit 18a and becomes attached to such unit 18a and to the surfaces 14a, 17a and 26a to form a vulcanized adhesion between the opposed contiguous faces of the units 11a and 18a. When the assembly process involves use and vulcanization of the film 31, the elastomer unit 18a may be preformed and vulcanized prior to assembly with such film and the unit 11a. When attaching the molded unvulcanized unit 18a (Figs. 1 and 2) to the carrier unit 11, that portion of the unit 18a contiguous with the surfaces of the unit 11 in opposed relation therewith, in becoming vulcanized and attached to these opposed surfaces, constitutes a vulcanized means for establishing an adhesion between the units 18 and 11.

Referring now to the third embodiment of the invention illustrated in Figs. 5 and 6, the doffer pads 27c have been attached directly to the annular plate surface 14c by vulcanization. A vulcanized film 31c, employed like the film 31 in Figs. 3 and 4 embodiment, is illustrated in Fig. 6 as an expedient for securing the pads 27c to the plate carrier surface 14c. It is contemplated, however, that the doffing pads 27 will be molded into form from vulcanizable elastomer material and pressed directly against the plate surface 14c where a vulcanized adhesion is formed pursuant to the application of heat and pressure to and between the parts 15c and 27c.

Having thus described a limited number of embodiments of the invention with the view of clearly and concisely illustrating the same, I claim:

5. A doffer assembly comprising a plate-like unit for rotation about a principal axis thereof, said unit having an annular face thereon disposed substantially within a plane at right angles to said axis and coaxial therewith, there being holes in said unit in registry with said face; an integral unit of elastomer material comprising an annular wafer-like web having an obverse face and a reverse face congruent with and disposed in flatwise contiguity with said face of the plate-like unit, a plurality of lugs projecting axially from said obverse face and spaced apart circumferentially thereof, and anchoring studs projecting from the reverse face respectively into said holes, and means adhesively joining said opposed faces throughout their area of opposed contiguity.

2. A doffer assembly comprising a plate-like unit for rotation about a principal axis thereof, said unit having an annular face disposed substantially within a plane at right angles to said axis and coaxial therewith and a shoulder projecting axially endwise of the unit along the inner perimeter of such annular face; an integral unit of elastomer material comprising an annular wafer-like web having an obverse face and a reverse face conforming to the annular face of the plate-like unit, and a plurality of lugs projecting axially from said obverse face and spaced apart circumferentially thereof, the inner perimetric edge of said web lying against said shoulder, said reverse face being in opposed contiguity with the annular face of the plate-like unit, and means adhesively joining said opposed faces throughout their area of opposed contiguity.

3. The combination set forth in claim 2 wherein a circular flange extends along the outer perimetric edge of said web and projects axially of the plate from the reverse face of the web in contiguity with the outer perimetric edge of the plate-like unit.

4. The combination set forth in claim 2 wherein the plate-like unit contains holes arranged in a circle about said axis and in registry with the annular face of the plate-like unit, and wherein the unit of elastomer material includes anchoring studs projecting from the reverse face thereof respectively conforming to said holes and projecting thereinto.

5. The combination set forth in claim 2 wherein a circular flange extends along the outer perimetric edge of said web and projects axially of the plate from the reverse face of the web against the outer perimetric edge of the plate-like unit, wherein the plate-like unit contains holes arranged in a circle about said axis and in registry with the annular face of the plate-like unit, and wherein the unit of elastomer material includes anchoring studs projecting from the reverse face thereof respectively conforming to said holes and projecting thereinto.

HOWARD F. PARKERTON.
